(57) **CLAIM**

The ornamental designs for a shelving/display unit, as shown and described.

DESCRIPTION

FIG. 1 is a perspective view of a first embodiment of a shelving/display unit, said first embodiment having two shelves and lettering on the sidewall.

FIG. 2 is a front elevational view of the shelving/display unit of FIG. 1.

FIG. 3 is a rear elevational view of the shelving/display unit of FIG. 1.

FIG. 4 is a left elevational view of the shelving/display unit of FIG. 1.

FIG. 5 is a right elevational view of the shelving/display unit of FIG. 1.

FIG. 6 is a top plan view of the shelving/display unit of FIG. 1.

FIG. 7 is a bottom plan view of the shelving/display unit of FIG. 1.

FIG. 8 is a perspective view of another embodiment of a shelving/display unit, said embodiment having a single shelf and lettering on the sidewall.

FIG. 9 is a front elevational view of the shelving/display unit of FIG. 8. The rear, left, right, top, and bottom views of the shelving/display unit of FIG. 8 are identical to the rear, left, right, top, and bottom views, respectively, of the shelving/display unit of FIG. 1.

FIG. 10 is a perspective view of another embodiment of a shelving/display unit, said embodiment having a two shelves and no lettering on the sidewall.

FIG. 11 is a front elevational view of the shelving/display unit of FIG. 10.

FIG. 12 is a perspective view of another embodiment of a shelving/display unit, said embodiment having a single shelf and no lettering on the sidewall.

FIG. 13 is a front elevational view of the shelving/display unit of FIG. 12.

FIG. 14 is a left elevational view of the shelving/display units of FIG. 10 and FIG. 12.

FIG. 15 is a right elevational view of the shelving/display units of FIG. 10 and FIG. 12.

FIG. 16 is a top plan view of the shelving/display units of FIG. 10 and FIG. 12; and,

FIG. 17 is a bottom plan view of the shelving/display units of FIG. 10 and FIG. 12. The rear view of the shelving/display units of FIG. 10 and FIG. 12 are identical to the rear view of the shelving/display unit of FIG. 1.
